UNITED STATES PATENT OFFICE.

BERNHARD SCHROER, OF HAMBURG, GERMANY.

WICKET.

1,101,338.

Specification of Letters Patent. Patented June 23, 1914.

Application filed December 29, 1913. Serial No. 809,373.

To all whom it may concern:

Be it known that I, BERNHARD SCHROER, a subject of the German Emperor, residing at Hamburg, Germany, have invented a new 5 and useful Wicket, of which the following is a specification.

The devices hitherto used upon the entrance or outer doors of apartments and the like which have observing holes (with or 10 without glass windows) or doors with security chains or the known observing mirrors which are mounted before the doors or windows, allow only the observation of a little part of the field of the view. Furthermore 15 more the known observing holes in doors which can be closed by covers or doors have only a very little field of view. The object of the invention is an improved security device for observing through the outer entrance doors of apartments and the like.

In the drawing two forms of construction of the device are represented.

Figure 1 shows a perspective view of the one form having an opened door. Fig. 2 is 25 a vertical section, Fig. 3 represents a perspective view of the back part of the device seen from the place of the observer. Fig. 4 shows a horizontal section through the device and a part of the entrance door. Fig. 30 5 represents a perspective view of the second form of construction and Figs. 6 and 7 are vertical sections on an enlarged scale in opened and closed position.

The observing device consists of a casing 35 *g* which is arranged behind a slit in the door. In the slit of the door is mounted a frame or casing for the mirrors whose front is closed by a glass plate *i*. For securing the mirrors a door *f* is pivoted to the outer side of the 40 slit in the apartment door. The door is opened by a spring *m* and can be closed by means of a pulling cord *f¹* by the observer behind the apartment door. The door *f* can be provided with sign boards and can be 45 made of metal porcelain wood or the like. Furthermore the door *f* can be made with a separate door for a letter box. The side-mirrors *c*, *d* are obliquely arranged against the inner side of the apartment or entrance 50 door. The side mirrors *c*, *d* are rigidly connected with the horizontal mirrors *e* and *b* and the glass plate *i*; thereby forming a rigid frame or casing.

Since the form of the mirrors has greater dimensions at the inner side of the apartment door the removing of the mirrors is only possible in the direction of the inner side of the apartment door and thereby the casing *g* of metal secures the frame or casing of mirrors in the oblique slit in the apartment door. The frame of the outer door *f* can be affixed to the casing *g* by means of pins or screw bolts.

The second form of construction seen in Figs. 5-7 shows side mirrors *c¹* *d¹* which are 65 mounted upon doors which are drawn toward the inner side of the apartment door by means of springs. By the opening of the door *f* the side mirrors *c¹*, *d¹* are pressed rearward by arms *f²* which are affixed to the 70 clap-door *f*. When the door *f* is lifted and has arrived at the horizontal position, the side mirrors *c¹*, *d¹* are no longer arrested by the arms *f²* and the spring causes them to move sidewise and then the door *f* covers all 75 the slit room and the mirrors therein. Furthermore the inner side of the door *f* can be provided with a mirror *f³*.

The operation and motion of the mirrors *c¹*, *d¹*, *f³* are the same as in the other form of 80 construction by a chain or cord *f¹*. The back wall consists of a wall *g¹* with a slit for observing.

I claim:

1. An observing security device for entrance doors consisting of a frame or casing formed by obliquely arranged mirrors (*c*, *d*, *b*), a door (*f*) pivoted to the front side of said frame or mirrors and means for opening or closing said door (*f*) in the inward 90 or outward direction by the observer.

2. Observing security device for entrance doors comprising in combination: a frame, formed by obliquely arranged mirrors (*c*, *d*, *b*), a door (*f*) pivoted upon said frame and 95 means for moving said door in the inward or outward direction and means for moving the singular particular side mirrors (*c¹*, *d¹*) in outward direction if the door (*f*) is outwardly moved.

BERNHARD SCHROER.
